CLAIM

The ornamental design for shelving system for cans or
the like, as shown and described.

DESCRIPTION

FIG. 1 is a perspective view of a shelving system for
cans or the like showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view, the rear view being
similar thereto.

FIG. 1.

FIG. 2.

FIG. 3.

FIG. 4.

FIG. 5.

FIG. 6.
